JOHN STOCKTON BEALLE, OF WALDORF, MARYLAND.

SAFETY REIN-CATCH.

1,259,073.

Specification of Letters Patent. Patented Mar. 12, 1918.

Application filed July 26, 1917. Serial No. 183,907.

To all whom it may concern:

Be it known that I, JOHN STOCKTON BEALLE, a citizen of the United States, residing at Waldorf, in the county of Charles 5 and State of Maryland, have invented certain new and useful Improvements in Safety Rein-Catches, of which the following is a specification.

This invention relates to rein catches and 10 more particularly to rein catches specially adapted for securing a rein or line so as to positively prevent accidental withdrawal of the same.

One of the main objects of the invention is 15 to provide a device of the character stated of simple construction and operation which may be used equally well for securing a check rein or the hand line. A further object is to provide a device so constructed as 20 to permit ready insertion of the rein into the same while positively preventing accidental withdrawal of the rein. Further objects will appear from the detailed description.

25 In the drawings:

Figure 1 is a perspective front view of a device constructed in accordance with my invention.

Fig. 2 is a side view of the same.

30 Fig. 3 is a detail of the locking member.

The catch is of approximately rectangular shape having the upper arm 1, lower arm 2, and end bar 3 integrally connecting the rearward ends of 1 and 2 which are disposed in parallel spaced relation. Arm 2 is provided, at its forward end, with an integrally upwardly directed bar 4 which is approximately $\frac{2}{3}$ as long as end bar 3. An intermediate inwardly directed arm 5 is 40 formed integrally with bar 4, adjacent the upper end thereof, and extends to within a short distance of the inner face of end bar 3 so as to leave an opening 6. The upper end of end bar 4 is extended to form an integral shoulder or abutment 7. The forward end of upper arm 1 is bifurcated to receive a lug 8 formed integral with a gravity latch 9 at the center of the upper end thereof. This lug 8 fits snugly between the 45 spaced ears 10 at the forward end of arm 1 and is pivotally secured between the same by a pintle 11 inserted through the ears and lug. Latch 9 is of such a length as to engage the inner face of member 7 so as to 50 have its outward movement positively limit-

ed thereby, the latch being thus normally maintained at a downward and inward inclination. This latch serves, normally, to close the space between the upper end of end bar 4 and the forward end of upper arm 1 60 so as to effectually prevent withdrawal of a rein from the catch.

This device may be secured directly on the saddle of the harness when used as a check rein catch, and may be secured on the 65 vehicle body when used as a catch for the lines. For securing the catch in operative position, I provide the lower arm 2 with a central downwardly directed screw stem 12. The catch will be mounted with the end bar 70 4 directed forwardly, when in use. If it is used as a check rein catch, the usual loop provided at the end of the check rein will be inserted between upper arm 1 and intermediate arm 5 by lifting the latch 9, for 75 which purpose lug 8 is disposed at an angle to the body of the latch as clearly shown in Fig. 3 of the drawings. The loop of the check rein will then be passed through the opening 6 and then forward about intermediate arm 5 and downward about the front end bar 4. When thus secured, there is 80 very small danger of the check rein becoming detached from end bar 4. However, if this should occur, the gravity latch 9, which 85 is normally in lowered position, will serve to effectually prevent complete withdrawal of the check rein from the catch. This device will be used in the same manner for securing the hand lines. The gravity latch 9, 90 while effectually preventing accidental withdrawal of the line, permits quick and easy insertion of the line into the securing device.

95 What I claim is:

A rein catch having an upper horizontal arm, a lower horizontal arm, an end bar connecting one end of the lower arm to one end of the upper arm, a shorter end bar extending vertically from the other end of the 100 lower arm, an intermediate horizontal arm formed integral therewith and of less length than said upper and lower arms so as to provide a passage-way about the inner end of said intermediate arm to permit insertion of 105 a rein between the intermediate and lower arms, said shorter end bar being provided with a shoulder at its upper end extending the full width thereof, and a gravity latch 110 pivotally secured to the other end of said

upper arm for movement toward and away from the intermediate arm, said latch having its free end beveled to fit snugly against the upper surface of the intermediate arm when in lowered position and being of such length as to engage the shoulder of the shorter end bar when in lowered position.

In testimony whereof I affix my signature in presence of two witnesses.

JOHN STOCKTON BEALLE.
